US00D996716S

(12) **United States Design Patent** (10) **Patent No.:** **US D996,716 S**
(45) **Date of Patent:** **** Aug. 22, 2023**

(54) **FALSE NAIL**

(71) Applicant: **Karmin Co., Ltd.**, Aichi (JP)

(72) Inventor: **Kaoru Kanada**, Aichi (JP)

(73) Assignee: **Karmin Co., Ltd.**, Toyohashi (JP)

(**) Term: **15 Years**

(21) Appl. No.: **29/853,677**

(22) Filed: **Sep. 17, 2022**

Related U.S. Application Data

(62) Division of application No. 35/511,529, filed on Sep. 11, 2020 (U.S. filing date under 35 U.S.C. 384), and having an international filing date of Sep. 11, 2020, now Pat. No. Des. 969,407.

(30) **Foreign Application Priority Data**

Jul. 3, 2020 (JP) D2020-13615
Sep. 11, 2020 (WO) DM/210291

CLAIM

The ornamental design for a false nail, as shown and described.

DESCRIPTION

FIG. 1 is a front view of a false nail of the claimed design; FIG. 2 is a back view of a false nail of the claimed design; FIG. 3 is a top view of a false nail of the claimed design; FIG. 4 is a left view of a false nail of the claimed design; and,

FIG. 5 is a perspective view of a false nail of the claimed design.

The bottom view is omitted because it is a mirror image of the top view. The right view is omitted because it is a mirror image of the left view.

1 Claim, 5 Drawing Sheets
